LEWIS CONDICT BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

VALVELESS PERCUSSIVE TOOL.

1,102,317.

Specification of Letters Patent.

Patented July 7, 1914.

Application filed November 13, 1912. Serial No. 731,061.

To all whom it may concern:

Be it known that I, LEWIS C. BAYLES, a citizen of the United States, residing at Easton, in the county of Northampton and 5 State of Pennsylvania, have invented a certain new and useful Improvement in Valveless Percussive Tools, of which the following is a specification.

This invention relates to fluid operated 10 percussive tools and more particularly to the so called valveless type of tool wherein the admission of the motive fluid producing the reciprocations of the piston is controlled by the movement of the piston itself.

15 The object of the present invention is to construct a tool which combines high efficiency with a low fluid consumption and at the same time is of simple and strong construction, a feature of the present design 20 being that large transverse borings in the piston used for admission and exhaust ports and which almost invariably result in breakage are entirely eliminated.

With this object in view I have devised a 25 tool a practical embodiment of which is shown in the accompanying drawings in which—

Figure 1 shows a side elevation of the tool. Fig. 2 shows a longitudinal section taken on the line 2—2 of Fig. 1. Fig. 3 shows a cross section taken on the line 3—3 of Fig. 2 and Fig. 4 shows a similar section on the line 4—4 of Fig. 2.

In the drawings the tool is shown as a 35 rotating hammer drill comprising a cylinder 1, a back head and handle portion 2 and a front head 3 these parts being held together by longitudinal bolts 4 which pass through lugs 5 and 6 on the back and front heads 40 respectively and are secured in place by nuts 7. The cylinder 1 consists of two portions, a rear portion or cylinder proper 8 of large diameter and a front portion 9 of considerably smaller diameter. Reciprocating in 45 the cylinder is a piston consisting of a head portion 10 of such a diameter as to fit in the large diameter portion 8 of the cylinder and an elongated shank portion 11 which closely fits the forward part 9 in the cylinder. On the inner surface of the smaller 50 diameter of the cylinder portion 9 is an annular inlet port 12 to which air or other fluid under pressure is supplied through an inlet opening 13. In the piston shank 11 55 near the piston head 10 is a depression 14

which is so placed and is of such a length that for a short portion of the piston stroke near the end of its forward travel, the inlet port 12 is placed in communication with the forward end of the cylinder portion 8 thus admitting fluid under pressure to the forward part of this chamber which constitutes the cylinder proper. A short distance forward of the inlet opening 13 is a second annular port 15 surrounding the piston which communicates by a passage 16 to the extreme rear end of the cylinder portion 8. A second set of depressions 17 forward of the depression 14 in the piston shank 11 serve to establish communication for a short period near the rearward end of the piston stroke between the annular port 12 and the annular port 15 thus admitting fluid under pressure to the rear end of the cylinder. Surrounding the large diameter portion 8 of the cylinder near its center is a shallow annular depression 18 from which a single exhaust port 19 leads to the atmosphere.

As shown, the tool is provided with means to rotate the drill steel comprising a fluted 80 rifle bar 20 engaging a fluted nut 21 in a bore 22 in the rear end of the piston. This rifle bar 20 is rotatably mounted in the back 85 heel of the cylinder and is provided with the usual ratchet mechanism 23. The forward part of the piston is provided with straight flutes 24 which engage similar grooves in a rotatable chuck 25 and through which slides drill steel 26. The drill steel is provided with a bore 27 air being provided to blow out the hole through a bore 28 in the piston.

In operation, supposing the parts to be in the position shown in Fig. 2 fluid under pressure will enter through the inlet opening 13 and will pass through the annular port 12, past the shank depressions 17, annular port 15 and passage 16 to the rear end of the cylinder driving the piston forward. As soon as the rear ends of the depressions 100 17 pass the annular port 12 the passage of fluid into the back end of the cylinder will be cut off, air thus being provided only during a short portion of the forward stroke of the piston. The fluid in the forward end of the cylinder is exhausted for a short portion of the stroke through the exhaust outlet 19. The depression 14 is so placed that the ingress of fluid to the forward end of the cylinder will be very quickly cut off so that 110

the rearward movement of the piston will be effected largely by the recoil of the piston and the expansion of the small amount of fluid admitted.

5. By reason of the fact that admission of fluid through the cylinder is controlled by a piston shank of comparatively small diameter leakage is largely avoided. Also the control of the admission of fluid to the ends 10 of the cylinder by the depressions allows the use of a piston whose strength is not impaired by transverse supply ports which practice has shown to be very detrimental to the strength and lasting qualities of the 15 piston.

It is to be understood that the present showing and description discloses only one specified modification of my invention and other forms and modifications are included 20 in the spirit and scope of the invention as expressed in the claims.

What I claim is:

1. In a valveless percussive tool, a cylinder having a front portion of small diameter and a rear portion of larger diameter, a piston having a head fitting said large portion and a shank fitting said small portion, a single live fluid inlet opening into said smaller portion, a depression in said piston shank for connecting said fluid inlet and the forward end of said large cylinder portion only near the front end of the piston stroke,

a passage leading from said cylinder at a point forward of said inlet opening to the rear end of said large cylinder portion, a depression in said piston shank for connecting said passage and said inlet opening only near the rear end of the piston stroke, and means for exhausting the cylinder.

2. In a valveless percussive tool, a cylinder having a front portion of small diameter and a rear portion of larger diameter, a piston having a head fitting said large portion and a shank fitting said small portion, a single live fluid inlet, said inlet opening into an annular port surrounding said smaller cylinder portion, a depression in said piston shank for connecting said fluid inlet and the forward end of said large cylinder portion only near the front end of the piston stroke, 50 a passage leading from said cylinder at a point forward of said inlet opening to the rear end of said large cylinder portion, a depression in said piston shank for connecting said passage and said inlet opening only 55 near the rear end of the piston stroke, and an exhaust port near the center of the large cylinder portion.

In testimony whereof, I have hereunto set my hand.
